UNITED STATES PATENT OFFICE.

JOHN F. CANNON AND MATTIE N. CANNON, OF ERICK, OKLAHOMA TERRITORY.

WINDOW-SHADE FIXTURE.

No. 824,707.

Specification of Letters Patent.

Patented July 3, 1906.

Application filed February 26, 1906. Serial No. 303,099.

To all whom it may concern:

Be it known that we, JOHN F. CANNON and MATTIE N. CANNON, citizens of the United States, residing at Erick, in the county of Greer, Oklahoma Territory, have invented certain new and useful Improvements in Window-Shade Fixtures, of which the following is a specification.

Our invention relates to that class of window-shades and fixtures embodying pivoted arms carrying the shade-roller and so arranged that they may be swung upwardly or downwardly, so that the shade may cover either the entire window or the upper or lower portion thereof, respectively.

The object of our invention is to provide an improved device of this character which will embody few and simple parts that may be easily operated to hold the fixture in raised or lowered position, which is provided with a spring-catch which will automatically lock the shade-fixture in its upper or raised position, and which will possess certain new and useful features hereinafter fully described and claimed.

For a full description of the invention and the merits thereof and also to acquire a knowledge of the details of construction of the means for effecting the result reference is to be had to the following description and accompanying drawings, in which—

Figure 1 is a perspective view of a portion of a window-frame with our improved window-shade fixture applied thereto, the parts being shown in their upper position. Fig. 2 is a similar view with the fixture lowered. Fig. 3 is a vertical longitudinal section. Fig. 4 is a horizontal section.

Corresponding and like parts are referred to in the following description and indicated in all the views of the drawings by the same reference characters.

Referring to the drawings, the numeral 1 designates a window-frame provided with stiles 2 of any desired construction for any design of window-sash. Brackets 4 are secured at the proper elevation to the respective stiles 2, and each bracket 4 is provided with two outstanding ears 5, preferably bent up from the metal of which the bracket itself is formed. The ears 5 are apertured and receive between them one end of arms 6, that are pivotally connected at such ends to the brackets by means of pivots 7. The free

ends of the arms 6 are connected together by an L-shaped plate 8, the angular members of which fit over the outer ends and sides, respectively, of the arms. One end of the L-shaped plate 8 is preferably permanently connected to its respective arm, while the other end of said plate is preferably detachably connected to its arm by means of one or more thumb-nuts 9. Attached to the inner sides of the arms 6 and at their outer ends are plates 10, preferably of metal formed with the usual square and round sockets for the reception of the gudgeons of the ordinary spring shade-roller 11. A stud 12 is secured to the inner side of one arm 6, (preferably the right-hand arm,) and an actuating-rod 13 is provided with an eye 14, whereby it is pivotally connected to said stud. The actuating-rod 13 is provided at its other end with a handle portion 15. The same arm is provided on its outer side with a pin or lug 16, with which the spring-catch 17 is designed to engage when the arms are swung to their raised or uppermost position. In the present instance the spring-catch 17 is in the form of a flat angular plate, one end of which is secured by screws or the like to the stile 2 and the other end of which projects outwardly from the stile and is provided with an orifice 18, into which the pin 16 is designed to snap. The outer end 19 of the spring-catch 17 is rolled upon itself, as shown at 20, to form a convenient means by which a cord or cable 21 may be secured. The cord extends through a screw-eye or similar loop 22, projecting out from the stile in horizontal alignment with the spring-catch and thence passes downwardly into convenient position for manipulation from the floor.

In the practical use of the device if it be desired to shade the upper portion of the window or the entire window the arms 6 are swung to their upper position, where they will be held by the spring-catch 17, and the shade may then be raised or lowered as much as desired. If, on the other hand, it be desired to shade the lower part of the window only, the spring-catch will be released by pulling on the cord or cable and the arms 6 lowered by means of the actuating-rod. The right hand of the operator may control the cord, while the left hand controls the actuating-rod.

From the foregoing description in connection with the accompanying drawings it will

be seen that we have provided a simple and efficient device of this character which can be cheaply manufactured and easily assembled. The shade may be readily attached and detached from its supporting-arms 6 by springing one of the arms 6 outwardly slightly after the thumb-nut that secures the L-shaped plate has been removed. The L-shaped plate forms considerable protection for the shade against dust, as it constitutes a partially-inclosing housing therefor.

Having thus described the invention, what is claimed as new is—

1. A window - shade fixture, comprising brackets arranged for attachment to the stiles of a window-frame, arms pivotally connected at one end to said brackets to swing in a vertical plane, a plate connecting the free ends of said arms, said arms being provided with sockets for the reception of the gudgeons of a shade-roller, and one of said arms being provided on its inner face with a stud and on its outer face with a pin or lug, an actuating-rod secured to the stud whereby the arms may be raised and lowered, a spring-catch projected out from the face of one stile and provided with an orifice in which the lug on the outer face of said arm is designed to snap and an actuating-cord secured to said catch and designed to draw the same outwardly from engagement with said lug.

2. A window - shade fixture, comprising brackets designed for attachment to the stiles of a window-frame, arms pivoted in said bracket to swing in a vertical plane and provided at their free ends with sockets designed to receive the gudgeons of a shade-roller, an L-shaped plate permanently connected at one end to one of said arms and having a detachable connection to the other end of the other arm whereby said arm may be sprung outwardly with relation to the plate to secure the shade-roller in place and remove it also, an actuating-rod secured to one of said arms, said latter arm being provided on its outer face with a lug, an angular spring-catch projecting out from one stile and provided with an orifice in which the lug is designed to snap whereby to hold the arms in raised position, and an actuating cord or cable secured to the free end of said catch, an eye or loop being provided on the stile adjacent to and in horizontal alinement with said catch and through which the cord or cable passes.

In testimony whereof we affix our signatures in presence of two witnesses.

JOHN F. CANNON. [L. S.]
MATTIE N. CANNON. [L. S.]
